CLAIM

The ornamental design for a storage bin, as shown and described.

DESCRIPTION

FIG. 1 is a front, left side perspective view of a storage bin, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof; and,

FIG. 9 is a perspective view of another state of the storage bin thereof.

The broken lines shown in the drawings depict portions of the storage bin that form no part of the claimed design.

1 Claim, 9 Drawing Sheets
